TRUCK DOCK BUMPER

John L. Bishop, Bethany, Okla., assignor to
DLM, Inc., Oklahoma City, Okla.

Filed Nov. 6, 1970, Ser. No. 25,862

Term of patent 14 years

Int. Cl. D8—99

U.S. Cl. D8—263

FIG. 1 is a front elevational view of a truck dock bumper showing my new design;

FIG. 2 is a rear elevational view thereof;

FIG. 3 is a top view thereof;

FIG. 4 is a bottom view thereof;

FIG. 5 is an end view thereof;

FIG. 6 is a view of the opposite end;

FIG. 7 is a sectional view taken along lines 7—7 of FIG. 1;

FIG. 8 is a sectional view taken along lines 8—8 of FIG. 1; and

FIG. 9 is a sectional view taken along lines 9—9 of FIG. 2.

I claim:

The ornamental design for a truck dock bumper, as shown.
